(57) **CLAIM**

The ornamental design for a case for mechanical pencil leads, as shown and described.

DESCRIPTION

FIG. 1 is a front, bottom, and left side perspective view of a case for mechanical pencil leads showing the new design. FIG. 2 is a rear, bottom, and right side perspective view thereof.

FIG. 3 is another front, bottom, and left side perspective view thereof showing a use state.

FIG. 4 is a front, top, and left side perspective view thereof showing a use state.

FIG. 5 is another rear, bottom, and right side perspective view thereof showing a use state.

FIG. 6 is a front elevational view thereof.

FIG. 7 is a rear elevational view thereof.

FIG. 8 is a right side elevational view thereof.

FIG. 9 is a left side elevational view thereof.

FIG. 10 is a top plan view thereof.

FIG. 11 is a bottom plan view thereof.

FIG. 12 is another front, bottom, and left side perspective view thereof showing a use state.

FIG. 13 is another front, top, and left side perspective view thereof showing a use state; and,

FIG. 14 is another rear, bottom, and right side perspective view thereof showing a use state.

The broken lines depict environmental subject matter that forms no part of the claimed design.

1 Claim, 14 Drawing Sheets
